UNITED STATES PATENT OFFICE.

MARTIN J. HAHRE, OF SMITHERS, BRITISH COLUMBIA, CANADA.

SAW GAUGE.

Application filed June 22, 1925. Serial No. 38,840.

This invention relates to saw tools and has particular reference to an improved saw gauge.

An important object of the invention is 5 to provide a gauge which may be firmly associated with the teeth of a saw for dressing the same.

A further object of the invention is the provision of a gauge of the above character which may be operated in an angular 10 position for various operations on the saw teeth.

A still further object of the invention is the provision of a saw gauge which is of 15 compact and durable construction and may be placed upon the market at a relatively low cost.

Other objects and advantages of this invention will become apparent as the description progresses.

In the accompanying drawing forming a part of this specification and in which like numerals are employed to designate corresponding parts throughout the same:

25 Figure 1 is a front elevation of my improved gauge shown in position for jointing saw teeth,

Figure 2 is a rear elevation showing the device in angular position for jointing raker 30 teeth,

Figure 3 is a top plan view of the device as shown in Figure 2,

Figure 4 is a transverse sectional view taken on the line 4—4 of Figure 1,

35 Figure 5 is a transverse sectional view taken on the line 5—5 of Figure 2,

Figure 6 is a similar view taken on the line 6—6 of Figure 1, and

Figure 7 is a rear elevation of the device 40 in its vertical operative position.

In the drawing, wherein for the purpose of illustration is shown the preferred embodiment of my invention, the numeral 10 generally designates the assembled gauge member composed of two complementary sections 11 and 12 hingedly connected for angular movement of one section relative to the other.

The upper section 11 is composed of a pair 50 of spaced vertical side plates 13 provided on the upper forward edge with a horizontal longitudinally extending flange 14. This flange is reinforced at its central portion by the provision of a pad 15 formed by constructing the central portion of the flange 14 of heavier material, the purpose of which

will be hereinafter more fully described. Formed on the lower forward edges of the side plates 13 and extending continuously thereover is a supporting flange 16, also of 60 heavier construction intermediate the side plates 13, to provide a solid structure. It will be noted that the upper flange 14 is disposed in spaced relation about the supporting flange 16 and is of substantially 65 wider construction as shown to advantage in Figures 2 and 4. The central portion of the flange pad 15 is provided with a pair of 70 internally threaded openings for receiving therein a set screw 17 positioned adjacent 75 the inner edge of the flange 14 and a machine screw 18 positioned adjacent the outer edge of the flange carrying a lock nut 19, the purpose of these screws will become apparent as the description progresses. It 75 can be readily seen from the foregoing construction that a comparatively wide slot is provided between the side plates 13 extending from the rear sides of these plates to the flanges 14 and 16 extending in alignment 80 with the forward sides of the plates.

The lower complementary section 12 embodies a pair of side plates 20 of somewhat wider construction and disposed directly beneath the upper side plates 13. The upper 85 and lower plates 13 and 20 are connected by hinges 21 permitting the upper side plate 13 to swing from a vertical aligned position to a right angular position. The lower forward edges of the lower side plates 20 90 carry a longitudinal tapered flange 22 extending longitudinally along the lower edges and between the plate, the outer edge of this flange being substantially in alignment with the outer edge of the supporting flange 16 95 when the sections are in vertically aligned positions.

Referring now particularly to Figures 2 and 3 it will be seen that the rear edge of the supporting flange 16 in the vertical arrangement of the upper section assumes an angular position relative to the longitudinal planes of the side plates 13 to provide a gauging surface. With particular reference to Figure 2 it will be noted that this 100 surface of the supporting flanges 14 and 16 between the side plates 13 assumes a downward slope from the left hand end, which is substantially even with the inner side of the side plate 13, to the right hand extremity which terminates somewhat below the inner side of the side plate when the 105 110

upper section is tilted in an angular position relative to the lower section. This edge also bears graduations having corresponding numerals mounted thereon to indicate 5 inches or any desirable units as shown at 23. The purpose of this construction will become apparent when the operation of the device is explained.

In use, when it is desired to joint the saw 10 teeth of a saw the sections 11 and 12 are positioned so as to cause the upper and lower side plates 13 and 20 to assume coplanar or aligned positions. A suitable file designated by the numeral 24 is then positioned 15 between the upper flange 14 and the supporting flange 16, being firmly retained in position by operation of the set screw 17. The body of the file will extend substantially beyond the supporting flange as clearly 20 shown in Figure 6, so that the upper edges of the saw teeth, shown in Figures 1 and 4 and indicated by the numeral 25, will contact therewith. The inner edges of the flanges 16 and 22 are moved in contact with 25 the sides of the teeth so as to properly guide the gauge and file.

When it is desirable to joint the raker teeth the upper body section 11 is swung about the hinges 21 so that the side plates 30 13 assume horizontal or right angular positions to the side plates 20. The device is positioned upon the saw teeth so as to engage or straddle the teeth between the flanges 14 and 16, as shown to advantage in 35 Figure 5, the lower flange 22 also engaging one side of the teeth so as to firmly brace the position of the gauge. Due to the angular position of the upper edge of the flange 16 the upper points of the teeth will 40 project above this flange in directly increasing ratio from the left to the right hand ends of the flange. The raker teeth are placed in the desired position against the supporting flange 16 and jointed by the 45 transverse movement of a file upon the angular gauging surface of the flange, the exact height of the raker teeth points, which are preferably shorter than the saw 50 teeth, may be regulated by the position of the raker teeth relative to the graduations which will indicate the proper height desirable for various operations. After the raker teeth have been properly jointed the upper 55 section 11 is then swung back to its aligned position and the saw teeth positioned against the forward edges of the flanges 16 and 22 so that the points of the raker teeth may be gauged by means of the machine screw 18 which is locked in proper position. The 60 gauge screw 18 is employed to determine the height of the raker tooth points. In applying the gauge screw to the teeth, the tiltable section is arranged in a raised position in vertical alignment with the stationary section. The screw 18 will then be 65

positioned in vertical alignment with the raker teeth so that the respective lengths of the raker tooth points can be ascertained.

It is obvious from the foregoing description that my improved gauge is especially adapted for jointing the raker teeth of the saw which operation may be accomplished in a very accurate and efficient manner. During the raker teeth jointing operation the gauge is retained in firmly associated position with the saw and the exact height of raker teeth relative to the saw teeth obtained without difficulty. 70 75

It is to be understood that the form of my invention herewith shown and described is to be taken as the preferred example of the same, and that various changes as to the shape, size and arrangement of parts may be resorted to without departing from the spirit of the invention, or the scope of the 80 85 subjoined claims.

Having thus described my invention, I claim:

1. A saw gauge comprising an upper section composed of side plates, a pair of spaced longitudinal flanges connected to and extending between the side plates, a set screw threadedly mounted in the upper flange, a machine screw threadedly mounted in the upper flange; and a lower section including a pair of side plates, a tapered flange formed on the lower edges of the lower plates, hinge members secured to the adjacent edges of the upper and lower sections adapted to permit the upper section to swing in an angular position relative to the lower section. 90 95 100

2. A saw gauge comprising a longitudinal frame including a lower section, an upper section tiltably connected to the lower section for vertical angular movement, the said lower section being arranged for engaging the side of the saw teeth, and the upper section adapted for vertical position when jointing the sawing teeth and right angular position when jointing the raker teeth. 105 110 115

3. A saw gauge comprising a longitudinal frame including a lower stationary section composed of a pair of spaced side plates arranged in alignment, a flange formed on the lower edges of the side plates and extending between the plates for unitary connection; an upper movable section hingedly connected to the lower section composed of a pair of spaced side plates, a pair of flanges arranged in spaced relation therebetween, the said upper movable section being arranged in a vertical position for jointing the sawing teeth, and arranged in a right angular position for engaging the upper edges of the teeth for jointing of the raker teeth. 120 125 130

4. A saw gauge comprising a lower stationary section, an upper movable section hingedly connected to the upper edge of the lower section having a pair of spaced

flanges formed thereon, the said flanges being arranged to engage a file for jointing the saw teeth, and arranged to straddle the upper edges of the teeth when the upper section is tilted in a right angular position for jointing of the raker teeth.

5. A saw gauge comprising a frame formed of hingedly connected sections, the lower section being relatively stationary and 10 arranged to engage the sides of the saw teeth, an upper section arranged for angular swinging movement having a pair of longitudinal spaced flanges formed on the forward portion, the said flanges being arranged 15 to receive the saw for jointing the sawing teeth, and adapted to be tilted so as to engage the upper point of the teeth between the flanges when in an angular position to permit convenient jointing of the 20 raker teeth, means for detachably securing a file between the said flanges, and a gauge screw adjustably carried by the upper flange for gauging the height of the teeth.
6. A saw tooth gauge composed of two 25 sections, the lower stationary section adapted to be positioned against the sides of the teeth, and an upper section hingedly connected with the lower stationary section arranged

for tiltable movement, the said upper section being adapted for right angular swinging movement to straddle the upper portions of the teeth when jointing the raker teeth to facilitate accurate jointing thereof.

7. In a saw tooth gauge comprising a lower frame section, an upper frame section 35 hingedly connected with the lower section adapted for vertical swinging movement, a gauge flange formed on the upper section having one side formed at an angular inclination with respect to the longitudinal 40 axis of the frame arranged so that when the upper section is tilted at a right angular horizontal position with respect to the lower section the angular side of the gauge flange will be positioned uppermost for jointing 45 the points of the raker teeth of the saw.

8. A saw tooth gauge comprising a lower stationary frame section, and an upper swinging section hingedly connected with the lower section adapted for swinging 50 movement in a vertical arc from a vertical position in vertical alignment with the lower section to a right angular horizontal position.

In testimony whereof I affix my signature.

MARTIN J. HAHRE.
